UNITED STATES PATENT OFFICE

2,626,139

MINING MACHINE

John Maurice Towler, Rodley, England, assignor
of one-half to Mavor & Coulson, Limited, Glas-
gow, Scotland

Application February 17, 1950, Serial No. 144,745
In Great Britain November 10, 1947

8 Claims. (Cl. 262—3)

1

This invention relates to machines for mining coal or other mineral and belonging to a previously proposed type having a large wedge-like cutter head adapted, in the advance of the machine, to strip the mineral from the face of a mineral seam by splitting the mineral along a plane behind the face. Where, as is usually desirable, the machine is double-ended—that is to say, is designed to work in each of its two directions of travel—there are two such cutter heads.

In one previously proposed construction, the machine was to comprise two relatively movable floor-engaging components which are propelled step-by-step along the face of a mineral seam to be mined; jacking means on at least one of said components for anchoring that component to the mine; and a propulsion unit interconnecting said components in order to propel each of them a step forwards while the other is temporarily stationary.

In accordance with the present invention, a mining machine of the type stated comprises a frame carrying the cutter head or heads, cylinder-and-ram propulsion apparatus, extensible and contractible roof-and-floor engageable jacking means to provide a temporarily fixed anchorage against which to apply the propulsion force, an anchorage assembly in which a component of the propulsion apparatus is incorporated and by which the jacking means is carried, the propulsion apparatus acting longitudinally between the anchorage assembly and the frame to advance them alternately, and guides on said frame for supporting and guiding the anchorage assembly during each advance thereof. In operation of the machine, the jacking means is operated to anchor the anchorage assembly to the floor of the mine, the cylinder-and-ram apparatus is operated to propel the frame alongside the mineral face so that the cutter head makes a cut, the jacking means is contracted to free itself from both the roof and floor, and said apparatus is operated to advance said assembly freely along the guides to take up a new position in readiness for the next cutting stroke.

Preferably, the propulsion apparatus includes a double-acting ram working in a hydraulic cylinder incorporated in the anchorage assembly, the ram having freedom of movement relative to the frame and being applicable at opposite ends to the ends of the frame so as to exert only a thrust or push thereon in either direction of action.

An example of a double-ended coal-mining

2

machine according to the invention is shown in the accompanying drawings, in which—

Fig. 1 is an elevation of the machine and Fig. 2 is a plan.

Fig. 3 is a sectional elevation of a hydraulic jack and associated parts as viewed in Fig. 1.

Fig. 4 is a sectional plan of the machine frame and the propulsion means, being a section approximately on the line 4—4 of Fig. 1.

Fig. 5 is a detail view to a larger scale, being a section on the line 5—5 of Fig. 1.

The cutter heads are indicated generally by 10 and 11 respectively. Each of these heads, in the example shown, comprises a leading cutter 12 arranged at an intermediate level, two cutters 13 and 14 above the cutter 12, and a floor cutter assembly 15, all of them having cutting edges working in approximately the same vertical plane A—A, Fig. 2, and they perform the main cutting operation on the coal. The vertical-plane cutting edges are indicated by 12A, 13A, 14A and 15A, respectively. Each floor cutter assembly 15 has also got a horizontal edge 15B, the assembly being in the nature of a deflecting shovel for removing coal from the floor and for lifting and deflecting the coal sidewise to a conveyor (not shown). Each cutter head also includes a horizontal-edged roof cutter assembly 16.

Each head carrying these several cutters is a heavy structure jointed to an end wall 17 or 18 of the frame of the mining machine.

Regarded generally, the mining machine consists of a heavy body, which comprises the aforesaid frame carrying the cutter heads 10, 11 and cylinder-and-ram components 19 and 20 for propelling the frame, in combination with roof-and-floor-engaging jacking means 21, 22 connected with the component 19 of the cylinder-and-ram apparatus to provide a temporarily fixed anchorage or abutment against which to apply the propulsion force. The propulsion cylinder 19 and the jacking means constitute an anchorage assembly. The frame includes, in addition to the end walls 17 and 18, two heavy horizontal bars 23 and 24 which rigidly interconnect said end walls. The bar 23 is arranged at a low level and close to the inner side of the machine; that is, the side which comes close to the face of the coal seam, represented in Fig. 2 by the plane A—A. The bar 24 is arranged at an intermediate level and at the outer side of the machine. These bars 23, 24 constitute guides upon which is slidably arranged a blocklike carriage indicated generally by 25. This blocklike carriage incorporates the cylinder component 19 of the cylinder-and-

ram propulsion apparatus and carries the cylinder component 21 of the jacking means; that is to say, the carriage 25 carries the whole of the propulsion apparatus and jacking means.

The cutter heads 10 and 11 are equipped with soles 10A and 11A respectively which are slidable upon the mine floor and which assist the floor cutter assemblies 15 to bear the entire weight of the machine.

In the example, the cylinder-and-ram propulsion apparatus is a single hydraulic unit of which the cylinder 19 is double-acting, being arranged in the carriage 25 longitudinally along the inner side of the machine. The ram 20 of the propulsion unit extends from both ends of the cylinder 19. The ram ends register with two buffers or abutments 26 on the end walls 17, 18 of the frame. The ram is very slightly shorter than the distance between the abutments 26, so that there is provision for slight relative longitudinal movement between the ram and the frame. Thus, when the ram is forced longitudinally in either direction relative to its cylinder 19 in the blocklike carriage 25, the ram and frame act like a unit which either advances relative to the temporarily stationary carriage 25 or rests stationary whilst the carriage advances. The fact that the ram 20 is structurally disconnected from the frame gives the important practical advantage that any distortion of the frame due to the very heavy work of the machine is not transmitted to the ram, which is left free of bending and torsional strains to work in its cylinder and to be subjected to purely longitudinal compression due to thrust in both directions on the frame.

With reference to the jacking means 21, 22, in the example this is a hydraulic jack, which is arranged vertically in the carriage 25 at the outer side of the machine. The jack is mounted in a casing or holder 27 incorporated in the structure of the carriage 25. The jack cylinder 21 is vertically slidable in the casing 27 and is formed with a part-spherical enlargement 21A about the centre of which the jack is tiltable in relation to the casing. The cylinder 21 and the piston of the piston-operated component 22 are double-acting. The jack cylinder 21 has a heavy foot or base 28 adapted to engage the mine floor when the jack is extended and which presses upwards against pads 29 on the underside of the casing 27 when the jack is fully contracted. The piston-operated component 22 has a head 30 adapted to engage the mine roof when the jack is fully extended and which rests upon facings 31 on the casting 27 when the jack is contracted. The head 30 is connected to the component 22 by a universal joint 32, so that the head is freely tiltable, within limits, in all directions. The arrangement is such that the jack can accommodate itself to undulations in the roof or floor.

The jack cylinder 21 is freely turnable relative to the casing 27 about the jack axis, which is indicated by a cross B in Fig. 2. Thus, when the jack is extended to engage the floor and roof, the machine is laterally pivotable about the axis B.

For the operation of the hydraulic cylinder-and-piston units 19, 20 and 21, 22 constituting the propulsion and jacking means of the machine, any appropriate hydraulic pumping plant is provided, such plant in the example being carried by the carriage 25. The plant comprises an electromotor-driven pump 33, a tank 34 from

which the pump draws the hydraulic liquid (namely oil) a manually operated control valve 35 for directing the hydraulic liquid to and from the appropriate ends of the cylinders 19 and 21 and appropriate piping 36 (Fig. 2). As Fig. 1 shows, the piping includes two flexible pipes 37, 38 communicating with opposite ends of the jack cylinder 21. The hydraulic plant, being of any conventional design, is shown more or less diagrammatically.

The leading cutter 12 of each of the cutter heads 10 and 11 is associated with a pad 39, the face of the pad occupying the cutting plane A—A; that is to say, the pad is arranged to slide against the newly cut coal face during each cutting stroke of the head 10 or 11 carrying it. Moreover, each leading cutter itself is angularly adjustable laterally so that its setting relative to the associated pad 39 can be adjusted to regulate the cutting action. As shown in Figs. 1 and 5, the cutter 12 is attached by a vertical pivot pin 40 to an arm 41 projecting forwards from the head 10 (or 11). Two adjustable grub screws 42 extending through the cutter come against a facing 43 on the arm 41 and thus fix the angular setting of the cutter. A swing bolt 44 anchored to the arm 41 passes through the cutter and serves to hold the screws 42 hard against the facing 43.

The operation of the machine is as follows: Assume that the machine as viewed in the drawings is to work towards the right; that is to say, the head 11 has to lead and act on the coal face whereas the head 10 has to trail idly. Assume also that the carriage 25 and jack 21, 22 are positioned as shown and that the hydraulic plant is in operation.

The first action of the machine is to thrust the head 11 forward to perform its cutting stroke. Accordingly, the control valve is manipulated so that the jack 21, 22 is extended. Thus, the jack cylinder 21 is forced downwards until its foot 28 engages the floor, after which the piston-operated component 22 rises until its head 30 engages the roof, so that the jack finally anchors itself and the carriage 25 between roof and floor. Next, the control valve 35 is operated so that the ram 20 of the propulsion unit is forced towards the right; that is, the propulsion unit is operated to push forwards the frame 17, 18, 23, 24. Thus a cutting stroke is performed by the head 11, the frame sliding upon the mine floor past the anchored jack and carriage. Next, the control valve 35 is operated so that the jack is operated to lower its head from the roof and lift its foot clear of the floor. The entire carriage 25 and everything carried by it are now supported by the frame clear above the mine floor. Finally, the control valve 35 is operated so that the propulsion unit acts in the opposite direction so that its ram 20 thrusts towards the left. This action causes the propulsion cylinder 19 with the carriage 25 and jack 21, 22 to slide forwards, free from obstruction by the floor or roof, along the frame guides 23, 24 in readiness for anchorage again.

When each cutting stroke is performed by the machine, the force of the stroke is directed in a plane from the central axis B of the jack to the approximate place of application to the coal of the main cutter edges 12A, 13A, 14A and 15A of the active head 11. In Fig. 2 the approximate plane of application is indicated by the arrow C, which is directed at an angle to the cutting plane A—A. Throughout the cutting stroke, not only does the frame 17, 18, 23, 24 continue to slide past the anchored jack 21, 22, but as the stroke

progresses the angularity of the line of application C with the cutting plane A—A decreases slightly by virtue of the pivotal relationship of the frame to the jack. By virtue of the universal mounting at 21A of the jacking means, the frame is free to follow undulations on the mine floor.

Thus it will be seen that, in the coal-mining machine described, the vertical roof-and-floor jack 21, 22 is outwardly offset from and pivotally related to the longitudinal propulsion cylinder-and-ram unit 19, 20 so that the inwardly inclined thrust from the ram towards the coal face produces an inward cutting influence on the leading cutter head 11, which influence is restricted by the pressure pad 39 on the cutter head.

As Fig. 2 shows, the centre of the total jacking pressure represented by the cross B is substantially offset outwards from the line of action of the propulsion ram 20, so much so that the approximate line of thrust represented by the arrow C is at an angle to the cutting plane A—A reasonably great enough to obviate or substantially reduce any tendency of the cutter head to work itself outwards from the face.

Moreover, the freedom of the frame to pivot about the anchorage at B obviates or minimises bending stresses in the frame; but as already explained, any such bending or other stresses to which the frame may be subject are not communicated to the propulsion apparatus 19, 20.

Patent application No. 144,763 having the same date as the present application describes and shows a mining machine the same as that herein described and shown in the accompanying drawings but claims an invention different from that hereinafter claimed.

I claim:

1. A machine for mining coal or other mineral and of the type stated comprising a frame, a cutter head carried by said frame, a carriage which is guided and supported by said frame for movement along the frame, extensible and contractible roof-and-floor engageable jacking means carried by said carriage to provide a temporarily fixed anchorage against which to apply machine propulsion force, cylinder-and-ram propulsion apparatus carried by said carriage, and ram ends included in said apparatus and arranged for abutting but movable relationship with the frame, said apparatus pushing through said ram ends against the frame in alternately opposite directions in order to advance the frame while the carriage is anchored and to advance the carriage while it is freed.

2. A machine for mining coal or other mineral and of the type stated comprising a frame, a cutter head carried by said frame, a carriage which is guided and supported by said frame for movement along the frame, extensible and contractible roof-and-floor engageable jacking means also carried by said carriage to provide a temporarily fixed anchorage against which to apply machine propulsion force, a double-acting propulsion power cylinder carried by said carriage, and a ram movable in both directions through said cylinder and extending therefrom in opposite directions so that its opposite ends are arranged for abutting but movable relationship with the frame, said ram ends pushing against the frame in alternately opposite directions in order to advance the frame while the carriage is anchored and to advance the carriage while it is freed.

3. A machine for mining coal or other mineral and of the type stated comprising a frame which

supports itself at opposite ends on a mine floor, a cutter head incorporated in said frame, cylinder-and-ram propulsion apparatus, guides also incorporated in said frame, said guides extending longitudinally between the opposite frame ends, a carriage which carries said apparatus and which is guided and supported clear of the mine floor by said guides for movement along the frame, extensible and contractible roof-and-floor engageable jacking means also carried by said carriage to provide a temporarily fixed anchorage against which said apparatus can apply machine propulsion force, the weight of said carriage, propulsion apparatus and jacking means being taken by said guides, and ram ends included in said apparatus and arranged to abut against the frame ends, said apparatus pushing through said ram ends against the frame in alternately opposite directions in order to advance the frame for the performance of a cutting stroke while the carriage is anchored and to advance the carriage while it is freed.

4. A machine for mining coal or other mineral and of the type stated comprising a frame which supports itself at opposite ends on a mine floor, a cutter head incorporated in said frame, longitudinal guides also incorporated in said frame, a double-acting propulsion power cylinder, a carriage which carries said cylinder and which is guided and supported by said guides for movement along the frame, extensible and contractible roof-and-floor engageable jacking means also carried by said carriage to provide a temporarily fixed anchorage against which said cylinder can apply machine-propulsion force, and a ram movable in both directions through said cylinder and extending therefrom in opposite directions so that its ends abut against the frame ends, the weight of said carriage, power cylinder, ram and jacking means being taken by said guides and said ram ends pushing against the frame in alternately opposite directions in order to advance the frame while the carriage is anchored and to advance the carriage while it is freed.

5. A machine for mining coal or other mineral and of the type stated comprising a longitudinal frame, oppositely directed cutter heads carried by said frame at its opposite ends, a carriage which is guided and supported by said frame for movement along the frame between its ends, extensible and contractible roof-and-floor engageable jacking means also carried by said carriage to provide intermediate the ends of the frame a temporarily fixed anchorage against which to apply machine propulsion force, cylinder-and-ram propulsion apparatus carried by said carriage, and ram ends included in said apparatus and arranged for abutting but movable relationship with the frame ends, said apparatus pushing through said ram ends against the frame ends in alternately opposite longitudinal directions in order to advance the frame in either of said directions while the carriage is anchored, so that a selected one of the cutter heads effects a cutting stroke, and to advance the carriage while it is freed.

6. A machine for mining coal or other mineral and of the type stated comprising a longitudinal frame, oppositely directed cutter heads carried by said frame at its opposite ends, a carriage which is guided and supported by said frame for movement along the frame, extensible and contractible roof-and-floor engageable jacking means also carried by said carriage to provide intermediate

the ends of the frame a temporarily fixed anchorage against which to apply machine propulsion force, a double-acting propulsion power cylinder carried by said carriage, and a ram movable in both longitudinal directions through said cylinder and extending therefrom in opposite longitudinal directions so that its opposite ends are arranged for abutting but movable relationship with the frame, said ram ends acting against the frame in alternately opposite longitudinal directions in order to advance the frame in either of said directions while the carriage is anchored, so that a selected one of the cutter heads effects a cutting stroke, and to advance the carriage while it is freed.

7. A machine for mining coal or other mineral and of the type stated comprising a longitudinal frame which supports itself at opposite ends on a mine floor, oppositely directed cutter heads incorporated in said frame at its opposite ends, cylinder-and-ram propulsion apparatus, guides also incorporated in said frame, said propulsion apparatus and guides being arranged to extend side-by-side longitudinally between the opposite frame ends, a carriage which carries said apparatus and in which is guided and supported clear of the mine floor by said guides for movement along the frame, extensible and contractible roof-and-floor engageable jacking means also carried by said carriage to provide intermediate the ends of the frame a temporarily fixed anchorage against which said apparatus can apply machine propulsion force, the weight of said carriage, propulsion apparatus and jacking means being taken by said guides, ram ends included in said apparatus and arranged to abut against the frame ends, said apparatus pushing through said ram ends against the frame in alternately opposite longitudinal directions in order to advance the frame in either of said directions for the performance of a cutting stroke by a selected one of the

cutter heads while the carriage is anchored and to advance the carriage while it is freed.

8. A machine for mining coal or other mineral and of the type stated comprising a longitudinal frame which supports itself at opposite ends on a mine floor, oppositely directed cutter heads incorporated in said frame at its opposite ends, longitudinal guides also incorporated in said frame, a double-acting propulsion power cylinder, 10 longitudinal guides also incorporated in said frame, a carriage which carries said cylinder and which is guided and supported by said guides for movement along the frame between its ends, extensible and contractible roof-and-floor engageable jacking means also carried by said carriage to provide intermediate the ends of the frame a temporarily fixed anchorage against which said cylinder can apply machine-propulsion force, and a ram movable in both longitudinal directions through said cylinder and extending therefrom in opposite longitudinal directions so that its ends abut against the frame ends, the weight of said carriage, power cylinder, ram and jacking means being taken by said guides and 20 said ram ends pushing against the frame in alternately opposite longitudinal directions in order to advance the frame in either of said directions while the carriage is anchored, so that a selected one of the cutter heads effects a cutting stroke, and to advance the carriage while it is freed.
